[57] CLAIM

The ornamental design for a file sheet for magnetic recording carriers, as shown and described.

DESCRIPTION

FIG. 1 is an enlarged perspective view of a file sheet for magnetic recording carriers showing my design;

FIG. 2 is a front view thereof;

FIG. 3 is a top plan view thereof;

FIG. 4 is a left side view thereof;

FIG. 5 is a right side view thereof;

FIG. 6 is a rear view thereof;

FIG. 7 is a bottom plan view thereof;

FIG. 8 is a cross-sectional view taken on line 8—8 of FIG. 3; and

FIG. 9 is a cross-sectional view taken on line 9—9 of FIG. 3.

FIG. 1

FIG. 2

FIG. 3

*FIG. 4**FIG. 5**FIG. 6**FIG. 7**FIG. 8*

FIG. 9
